Primary Examiner — John A Voytek

(74) Attorney, Agent, or Firm — Burr & Forman LLP

(57) **CLAIM**

The ornamental design for the wheel for a robotic mower, as shown and described.

DESCRIPTION

FIG. 1 is a perspective view of a wheel of the present invention;

FIG. 2 is a back view of the wheel of FIG. 1;

FIG. 3 is a front view of the wheel of FIG. 1;

FIG. 4 is a left side view of the wheel of FIG. 1;

FIG. 5 is a right side view of the wheel of FIG. 1;

FIG. 6 is a top view of the wheel of FIG. 1; and,

FIG. 7 is a bottom view of the wheel of FIG. 1.
